UNITED STATES PATENT OFFICE.

ALFRED M. MARTIN, OF CHICAGO, ILLINOIS.

LOOSE-LEAF-BINDER DEVICE.

Application filed March 29, 1926. Serial No. 38,198.

These improvements relate to devices ordinarily termed files or binders, and which are usually in book form, for holding a series, or many series, of cards or sheets in overlapped relation, such devices usually having two rows of prongs on body members which are hinged together.

The improvements have more particular relation to such binders having means for shifting cards or sheets from one longitudinal position therein to another.

In my copending application known as Serial Number 26,619, filed April 29, 1925 I have shown a loose-leaf binder having mounted thereon a sheet-shifting device adapted to be moved into operative position to shift cards or sheets when the book or binder is open, and to occupy an out-of-the-way position within the binder when the binder is closed, the shifting device being permanently attached to the binder so as normally to remain connected therewith at all times.

According to the present improvements the sheet-shifting device is a free unit which is applied to the binder by the operator. Through an association of the shifting device with supporting means carried by the binder a coaction is made between the binder and the shifting device for positioning the latter and maintaining it in its proper relation to binder prongs while cards or sheets are being transferred therefrom to the shifting device, and while the latter is then moved longitudinally, and while the cards or sheets are then transferred back to binder prongs to lie in another longitudinal position in the file. According to these improvements too, while the sheet-shifting device may be removed bodily from the binder or file when it is not in use, there is a further feature of advantage in provisions whereby the sheet-shifter may occupy an out-of-the-way position in the binder when the binder is closed, to the end that the device may always be available for use, may be free from the danger of loss and so relieve the operator of responsibility for its safety, and, through its ever-ready character, save time.

In the drawings Figure 1 is an end view of a non-shift binder equipped with shifting means according to these improvements and showing the out-of-the-way position of the shifting device when the book or binder is closed; Fig. 2 is a view similar to that of Fig. 1, but with the book open, and show-

ing the out-of-the-way position of the shifting device at such time also; Fig. 3 is a top plan of the book or binder looking down on the device as illustrated in Fig. 2; Fig. 4 is a sectional view of the binder on the line 4-4 of Fig. 2 with the sheet-shifting plate in its normal position for use; Fig. 5 is a view similar to that of Fig. 2, but viewed from the opposite end of the device, showing in full lines the shifting member in position to receive cards or sheets from binder prongs or to transfer them to binder prongs; and Fig. 6 is a fragmentary face view of a series of perforated cards or sheets in overlapped relation as used in the device. In the several figures the front and back covers of the book-like structure are only fragmentarily shown.

In the particular device illustrated the two body members A and B may be considered to be of wood covered with fabric and united by a pair of metal hinges 10. The covers 11 have a hinge-like connection with the body members respectively at 12 through the fabric covering common to the body and to the covers, and thus the main frame structure of the device is substantially in the form of a book which opens and closes through the hinged connections 10 to assume the several relative positions illustrated. As to the fundamental binder parts thus specified I have illustrated only what is old. So far as the present improvements are concerned the binder per se may be according to any one of a large number of well-known constructions.

The body member A has a row of prongs 13 while the body member B has a similar row of prongs 14, these prongs being carried rigidly by the body members respectively and being of arcuate formation on a common radius leading from the axis 10. As shown in Figs. 3 and 4 the binder prongs 13 and 14 are offset longitudinally with respect to each other and are therefore in overlapping relation when the book is closed as shown in Fig. 1.

There are provided, as a special feature of binder construction for the present purposes, such a plurality of prongs 13 and 14, and the adjacent ones of each series or row are so close together, as to hold a longitudinal series, or a plurality of such series, of sheets or cards in overlapped relation, as fragmentarily shown in Fig. 6.

In Fig. 6 the upper portion of each of such

cards or sheets is exposed, as to exhibit reference data, these several sheet units being identified as C, D, E, F, G, H and I. The sheet I is shown as broken away close to the top to show a portion of underlying sheet H, and that sheet is broken away showing a portion of underlying sheet G, and so on, illustrating the fact that the cards or sheets are in overlapped relation to each other and 10 adapted so to be held by binder prongs. It is to be understood that holes 15 punched in the sheets register with other such holes when the sheets are in such overlapped relation, and each sheet of the series illustrated 15 may be understood to be like every other sheet thereof and as being provided with a row of binder-prong holes 15 equidistant from each other, the arrangement providing that several, say three, of the binder prongs 20 pass through each of the overlapped cards or sheets.

In the well-known device of my Patent No. 1,269,497 of June 11, 1918 one body member is shiftable longitudinally relative to the other thereof on the hinged connections to 25 provide for transferring cards or sheets to a different longitudinal position in the binder, to accomplish important objects and advantages pointed out in my said patent. 30 According to the present improvements the two body members as A and B are not movable longitudinally relative to each other. It is an object of the present improvements to accomplish the results of a shift binder 35 without shifting a large mass of book elements and many cards or sheets, thus saving labor and time and avoiding certain inconveniences in operation. It is an object to provide simple, light-weight and easily operable sheet-shifting means for such a binder, and to provide a binder having sheet-shifting means as an adjunct or auxiliary feature thereof. It is also an object to provide a 40 construction of binder and sheet-shifting device whereby the latter may remain in the binder in an out-of-the-way position when not in use, and where it is at all times readily available.

The sheet-shifting means illustrated consist first of a plate 16, shown as being substantially rectangular in contour, as being relatively long, namely almost as long as the binder body, and as being provided with a plurality of slightly curved prongs 17 arranged in a row near what is normally the upper edge of the plate. The prongs 17 are shown as being spaced apart equidistantly and to the same extent as are the binder prongs 13 or 14, and these sheet-shifting prongs have therefore the same relationship to the holes 15 in the cards as do the binder prongs. The prongs 17 are relatively short, and, as shown by Fig. 5, they may be brought into such an overlapping relationship with the prongs 14 that the end

portions of the prongs 17 and the end portions of the prongs 14 may have a common longitudinal projection.

The sheet-shifting feature includes also means for supporting the prong-carrying plate 16 for rocking movements in directions toward and away from the ends of binder prongs and for sliding longitudinal movements. Such supporting means may be variously embodied. Figs. 2 and 5 well illustrate plate-supporting means in one of such various embodiments, and comprises a pair of standards 18, one thereof being positioned near each end of the binder body and, in the form shown, each standard comprises a narrow, flat and straight plate 19 and a plate 20 similar to plate 19 except that at its upper end it is bent outwardly and upwardly at 20^a to form with the upper end of the plate 19 a recess or seat 21 adapted to receive for 85 rocking and sliding movements therein the lower edge of the pronged plate 16. These two plates 19 and 20 are held face to face upon each other and upon the body member B by screws 22.

The sheet-shifting operation is usually performed upon sheets lying on the right-hand side of the binder when open. In Fig. 5 we are supposed to be facing the operator, and will therefore assume that with his left hand he has placed the pronged plate 16 in the two aligning seats 21 while with his right hand he has lifted certain sheets 23^a desired to be shifted and has passed them over upon shifter prongs while still upon the end portions of binder prongs; that thereupon, while holding the cards on the plate and the plate on the support, by rocking or swinging the shifter plate on the axis of its support and into its dotted-line position shown in Fig. 5, the ends of the prongs 17 having cleared the ends of the prongs 14, the plate 16 is moved with a sliding contact upon the supporting means into some other longitudinal position, say the distance between two, three or more of the adjacent holes in the cards or sheets, and that thereupon the plate 16 is swung back into its full-line position in Fig. 5 and the cards or sheets thereon transferred back to binder prongs, to occupy then another longitudinal position in the binder.

A notable feature of advantage in the operation just described is in the fact that the operator is handling a very light-weight object over which he has perfect control and, with respect to the cards or sheets, is manipulating only the particular ones the position of which it is desired to change.

From Fig. 1 it will be noted that the shifter there occupies a position for the most part between the body members A and B and with only the upper end portion thereof containing the prongs extending (and well within the space allowance) into the space

beneath the binder prongs in that figure and entirely out of the way and out of contact with sheets as 23 carried thereby. A special feature of the construction in this respect is so to form or apply the hinge connections as to provide space for this device when the binder is closed.

From Fig. 2 it will be observed that when the binder is open the sheet-shifting plate 16 lies upon the body member B and is still in an out-of-the-way position, so that all of the various manipulations of the cards or sheets not involving the use of the shifter may be performed without reference thereto. Means are provided for holding the plate 16 in the relative positions of it shown in Figs. 1 and 2 whereby the book may be opened and closed freely and from time to time as desired, and for consultation of any series 20 of sheets in the book, without any consideration of the presence of the shifting device therein. The means provided for this purpose include the supporting means 18 and the provision of holes 25 (Figs. 3 and 4) in the plate 16 through which the upper ends of the supports 18 extend when the plate is applied thereto for holding effects. Fig. 3 well illustrates how the plate 16 is so held.

I have also shown means for locking the two body members in closed position, a feature common to hinged binders. The means illustrated are a spring 27 secured to the body at 28 (top of Fig. 3) and having a catch projection 29 intermediate its ends and opposite one of the post-like supports 18, which support has a hole 30 therethrough (shown by dotted lines in Fig. 5) into which the projection 29 extends when the body members are locked together as in Fig. 1. By pressing down the free end of the spring 27 (Fig. 1) the projection 29 comes out of the hole 30 freeing the body members to be opened.

This application is a continuation of my copending application Serial No. 26,619, filed April 29, 1925, entitled Loose-leaf binders.

I contemplate as being included in the present improvements all such variations and departures from and such modifications and equivalents of what has thus been specifically illustrated and described as fall within the scope of the appended claims.

55 I claim:

1. The combination with a loose-leaf binder having opposed rows of prongs for holding cards or sheets in overlapped relation, of sheet-shifting means comprising a plate having a row of prongs thereon, and supporting means for said plate for holding said plate with the prongs thereof in position to receive cards or sheets from the binder prongs and for holding the plate for sliding longitudinal movements.

2. The combination with a loose-leaf binder having opposed rows of prongs for holding cards or sheets in overlapped relation, of sheet-shifting means comprising a plate having a row of prongs thereon, and supporting means for said plate having a relatively fixed relation to the binder for holding said plate with the prongs thereof in position to receive cards or sheets from the binder prongs and for holding the plate for sliding longitudinal movements.

3. The combination with a loose-leaf binder having a pair of body members hinged together, with a row of prongs on each body member for holding cards or sheets in overlapped relation, of sheet-shifting means comprising a plate having a row of prongs thereon, and supporting means for said plate upstanding from the binder and having guide means thereon for holding said plate with the prongs thereof in position to receive cards or sheets from the binder prongs and for holding the plate for transverse swinging and for longitudinal sliding movements.

4. In a loose-leaf binder of the non-shift type and having two opposed rows of prongs for holding cards or sheets in overlapped relation, the combination therewith of means carried by the binder for supporting a sheet-shifting device for movement thereon and for ready removability from the binder when not in use and to occupy a position substantially between the rows of binder prongs to receive cards or sheets from prongs of one row thereof when in use, and a sheet-shifting device having a row of prongs thereon operatively supported by said supporting means to occupy said position when in use and to swing in directions toward and away from the binder prongs.

5. In a loose-leaf binder having a pair of body members hinged together, with a row of prongs on each body member directed inwardly, the combination therewith of means carried by the binder for supporting, for ready removability, a longitudinally-shiftable sheet-shifting device in operative relation to a row of the binder prongs to receive sheets or cards therefrom, and a longitudinally-shiftable sheet-shifting device so supported on the binder and having means for engaging sheets transferred to the shifting device from binder prongs.

6. In a loose-leaf binder having a pair of body members with a row of prongs on each directed inwardly, the combination therewith of means on the binder for supporting for ready removability a longitudinally-shiftable sheet-shifting device in operative relation to a row of the binder prongs to receive sheets or cards therefrom, and a longitudinally-shiftable sheet-shifting device so supported on the binder and having prong means for engaging sheets trans-

ferred to the shifting device from binder prongs.

7. In a loose-leaf binder of the non-shift type having a row of prongs for holding 5 cards or sheets in overlapped relation, the combination therewith of a plate having a row of substantially short prongs thereon and adapted to be positioned substantially opposite the ends of binder prongs with its 10 prongs in overlapped relation to binder prongs to receive cards or sheets from such binder prongs, with means carried by the binder for supporting said shifting device for ready removability when not in use and 15 for swinging movements in directions toward and away from free ends of the binder prongs and for longitudinal movement when in use.

8. The combination with a loose-leaf 20 binder having opposed rows of prongs adapted to hold thereon respectively perforated cards or sheets in overlapped relation, of a sheet-shifting device including a longitudinally-shiftable plate having prongs 25 and adapted to be positioned substantially opposite one row of the binder prongs to receive from the binder prongs cards or sheets, and means carried by the binder for supporting the shifting device in its operative 30 relation to the binder prongs and for ready removability from the device when not in use.

9. In a loose-leaf binder of the character 35 described, the combination of a pair of body members each having a row of prongs thereon, the body members being hinged together by means providing a space between them adjacent to the hinge means, for accommodating 40 a sheet-shifting unit between the body members when the binder is closed.

10. In a loose-leaf binder of the character described, the combination of a pair of body members each having a row of prongs thereon, the body members being hinged together 45 together by means providing a space between them adjacent to the hinge means, for accommodating a sheet-shifting unit between the body members when the binder is closed, and a sheet-shifting unit occupying 50 said space.

11. In a loose-leaf binder of the character 55 described, the combination of a pair of body members each having a row of prongs thereon, the body members being hinged together by means providing a space between them adjacent to the hinge means, for accommodating a sheet-shifting unit between the body members when the binder is closed, a sheet-shifting unit occupying said space, and means for holding said sheet-shifting unit in said space.

12. In a loose-leaf binder of the character 60 described, the combination of a pair of body members each having a row of prongs thereon, the body members being hinged together

by means providing a space between them adjacent to the hinge means, for accommodating a sheet-shifting unit between the body members when the binder is closed, a sheet-shifting unit occupying said space, 70 and means for holding said sheet-shifting unit readily releasable for withdrawal from the binder when the binder is open.

13. In a loose-leaf binder of the non-shift type having opposed rows of prongs for 75 holding cards or sheets in overlapped relation, the combination therewith of a plate having a row of prongs thereon adapted to be positioned with its prongs directed toward the binder prongs, with post-like supporting means on the binder for supporting said shifting device, when the binder is open, for swinging movements in directions toward and away from free ends of binder prongs and for longitudinal movements, said post-like means being arranged to occupy an out-of-the-way position when the binder is closed.

14. In a loose-leaf binder having a pair 80 of body members hinged together, with a row of prongs on each body member directed inwardly, the combination therewith of means on the binder for supporting a sheet-shifting device in its operative relation to a row of the binder prongs to receive cards or sheets therefrom, for longitudinal and rocking movements, and for ready 85 removability from the binder, and a sheet-shifting device adapted so to be supported by the binder and having means for engaging sheets transferred to the shifting device from binder prongs, with means for holding said sheet-shifting device in an out-of-the-way position in the binder when the sheet-shifting device is not in use.

15. In a loose-leaf binder having a pair 90 of body members hinged together, with a row of prongs on each body member directed inwardly, the combination therewith of means on the binder for supporting a sheet-shifting device in its operative relation to a row of the binder prongs to receive cards or sheets therefrom, for longitudinal 95 and rocking movements, and for ready removability from the binder, a sheet-shifting device adapted so to be supported by the binder and having means for engaging sheets transferred to the shifting device from binder prongs, and means for holding 100 said shifting device in an out-of-the-way position adjacent to the hinge means thereof and partly between the body members at the hinge means when the binder is closed.

16. In a loose-leaf binder having a pair 105 of body members hinged together, each body member having a row of prongs for holding cards or sheets in overlapped relation, the combination therewith of a plate having a row of prongs thereon adapted to be positioned with its prongs directed toward the 110

- binder prongs, with a plurality of post-like supports on the binder for supporting said shifting device for swinging movements in directions toward and away from the free 5 ends of the binder prongs and for longitudinal movements, spring catch means for holding the body members in closed position, one of said supports coacting with said catch means thereto.
- 10 17. In a loose-leaf binder having a pair of body members hinged together, each body member having a row of prongs for holding cards or sheets in overlapped relation, the combination therewith of a plate 15 having a row of prongs thereon adapted to be positioned with its prongs directed toward the binder prongs, with a plurality of post-like supports on the binder for supporting said shifting device for swinging movements in directions toward and away 20 from the free ends of the binder prongs and for longitudinal movements, spring catch means for holding the body members in closed position, one of said supports coacting with said catch means thereto, said 25 plate having a plurality of openings therein to accommodate said supports respectively whereby said plate may be held by said supports when not in use.

ALFRED M. MARTIN.
